UNITED STATES PATENT OFFICE

2,159,315

LATCH BOLT

Roy E. Blue, Detroit, Mich., assignor to Chrysler Corporation, Highland Park, Mich., a corporation of Delaware

Application March 16, 1938, Serial No. 196,127

7 Claims. (Cl. 292—2)

This invention relates to an improved latch bolt, and particularly to a device of this character for cooperating with the striker plate of a vehicle door.

5 One object of the invention resides in the provision of an improved latch bolt having a keeper engaging end portion around which is disposed a wear resisting sheathing, and having a resilient material interposed between the sheathing and the keeper engaging end portion to serve as a yieldable back and sound insulator.

Other objects of the invention are to provide a latch bolt of this kind which completely insulates the wear resisting sheathing from the keeper engaging end portion while resiliently accommodating relative yielding movement therebetween; and to provide in a latch bolt of this character a means for conveniently holding the wear resisting sheathing, the resilient material and the keeper engaging end portion in an assembled state whereby the sheathing and the end portion are completely insulated from each other and while resilient relative yielding movement is accommodated therebetween.

25 Additional objects of the invention are to provide in a latch bolt of this character a resilient means for cushioning the action of the striker plate with which it cooperates during latching operation; and to provide resilient means of this character which has sound insulating properties for interrupting the direct transmission of sound vibrations to the structure on which the latch bolt is mounted and for deadening the noise resulting from engagement and disengagement 30 of the latch bolt and the striker plate.

Other objects and advantages of the invention will be more apparent from the following description taken in connection with the accompanying drawing, in which:

40 Fig. 1 is a partial horizontal sectional view of a door and associated door post structure showing a latch bolt embodying the invention.

Fig. 2 is a fragmentary side elevational view of a latch bolt embodying the invention taken approximately as indicated by the line 2—2 of Fig. 1.

Fig. 3 is a sectional view along the line 3—3 of Fig. 2.

Fig. 4 is a fragmentary side elevational view 50 of a latch bolt corresponding to Fig. 2 but illustrating a modified form of the invention.

Fig. 5 is a sectional view taken as indicated by the line 5—5 of Fig. 4.

In the form of the invention illustrated in 55 Figs. 1 to 3, inclusive, the improved latch bolt is

embodied in a vehicle body, but it will be understood that it may be used with any two members which move relative to each other, without departing from the scope of the invention.

The improved latch bolt, generally indicated by the numeral 10, is slidably mounted as at 11 and 12 in the door structure 13 and also in a bearing element 14 of the door structure. This latch bolt comprises a slotted portion 15 having a substantially flat end face or shoulder 16, and a reduced end portion 17 slidably mounted in the bearing element 14. A yieldable means, such as the spring 18 which is interposed between the bearing element 14 and the body portion of the latch bolt, normally urges the latch bolt outwardly against the action of which it may be retracted by turning a handle 19, journaled in the door structure 13, in a clockwise direction. The door handle 19 has a stem 20 extending into the door structure and provided on its inner end with a cam 21 which bears against the shoulder 16 formed on the latch bolt.

Formed on the keeper engaging end portion of the latch bolt 10 is a reduced portion 22 having spaced notches 23 formed in and open at the upper side and adjacent lateral side portions thereof, as viewed in Figs. 1 and 3. A transversely extending groove 24 is formed in the lower side of the reduced part 22. A layer of sound-absorbing, resilient material, such as rubber 25, is disposed around the reduced portion 22. Surrounding the layer of rubber 25 is a wear resisting sheathing 26 having a pair of spaced, inwardly extending flanges 27 on one of its end portions which extend into corresponding upper notches 23 and having a flange 28 extending entirely across its other end portion and disposed in the groove 24. These flanges hold the sheathing 26 and the layer of rubber 25 in place. The sheet-like sound absorbing material 25 is reversely bent within the notches 23 and groove 24 and the flanges 27 and 28 are disposed between the adjacent side sections of these reversely bent parts of the layer 25. The sheathing 26 preferably comprises resilient material and is preferably so formed as to normally contract in a manner which causes it to resiliently grip upon the outer end portion of the latch bolt and to urge the flanges 27 and 28 into the notches 23 and groove 24 respectively. If desired, the 40 sheathing 26 may be formed of any suitable material which will take a substantially permanent set and in this case the sheathing may be squeezed to a tight fitting relationship as the outer end of the latch bolt and the flanges are 55

forced into the notches and groove in any suitable manner. The sheathing 26 and rubber layer are thus securely held against both lateral and longitudinal displacement from the bolt. If 5 desired, the rubber layer may be adhered or bonded by vulcanization to the bolt and sheathing or to either thereof.

The sheathing 26, the rubber 25 and the reduced portion 22 are so constructed and arranged that the reduced portion 22 and the sheathing 26 are completely insulated from each other against jar and noise, and accommodate through the rubber 25, resilient relative yielding movement therebetween.

15 Any suitable member, such as the striker plate 30, may be used to cooperate with the improved latch bolt 10 in releasably holding the door structure 13 against opening. The striker plate 30 is suitably fixed at 31 to a door post 32 or other 20 structure similarly located with respect to the door 13.

Formed on the side of the striker plate 30 opposite the latch bolt 10 are notches 33 and 34. Shoulders 35 and 36 are provided adjacent each 25 notch 33 and 34 respectively, and ramps 37 and 38 are provided on the right side of the striker plate adjacent the shoulders 35 and 36 respectively.

In the operation of this particular embodiment 30 of the invention, as the door is moved toward its closed position of Fig. 1, the rounded outer extremity of the sheathing 26 engages the striker plate 30 at the first ramp 38, and further closing movement of the door causes the latch bolt 10 to be urged inwardly against the action of the spring 18 until the sheathing 26 passes over the shoulder 36. When the latch bolt sheathing reaches this position the latch bolt is projected outwardly by the spring 18 and into the first 40 notch 34 of the striker plate 30. The sheathing 26 receives the impact from its contact with the striker plate as the former is projected into the notch 34, but this impact is cushioned and the resulting noise is insulated from the door 13 by 45 the rubber 25.

Further closing movement of the door 13 causes the latch bolt 10 to be retracted against the action of the spring 18 by the second ramp 37, and when the door 13 has reached its fully 50 closed position the sheathing 26 of the latch bolt is projected quietly into the second notch 33 where the door 13 remains insulated from the post 32 by the rubber 25 until the handle 19 has turned clockwise to bring the latch bolt 10 out 55 of latching engagement with the striker plate 30.

Referring now to Figs. 3 to 5 in which is shown a modified form of the improved latch bolt, the construction and operation is substantially the same as that illustrated in the earlier described 60 embodiment. Members of different construction but similar function to those of the aforesaid embodiment have been indicated by primed reference characters. In this form of the invention the end portions of the sheet metal of which 65 the sheathing 26 is formed are bent inwardly to provide flanges 27' and 28' which extend into transversely extending grooves 23' and 24', respectively, in the reduced end portion 22' of the bolt. The end portions of the rubber layer 25' 70 are reversely bent within the groove and the flanges 27' and 28' are disposed between adjacent sections of the reversely bent part of this rubber layer. The sheathing 26' may comprise resilient material having a contracting gripping fit on the 75 outer end of the latch bolt or it may be formed

of material which may be crimped firmly thereon as explained in connection with the form of the invention shown in Figs. 1 to 3, inclusive. Relative lateral movement between the sheathing 26' and the rubber is prevented by depressing a portion of the former as at 39. The rubber of the improved latch bolt serves to cushion the engagement of the latter with the door latch plate and also prevents the direct transmission of sound vibrations from the bolt to the metal panel structure of the vehicle. In this manner, amplification of the sound created by the metal-to-metal contact of the sheathing 26 and the striker plate 30 is reduced.

Various modifications and changes may be effected in the illustrated applications without departing from the spirit of the invention or from the scope of the appended claims.

What I claim is:

1. A latch bolt comprising a main body portion 20 having a keeper engaging end portion, a sheathing disposed around said keeper engaging end portion, and resilient material interposed between said sheathing and said keeper engaging end portion.

2. A latch bolt comprising a main body portion having a keeper engaging end portion, a sheathing disposed around said keeper engaging end portion, and means between said sheathing and main body portion comprising resilient material having sound insulating properties for substantially completely insulating said keeper engaging end portion from said sheathing while resiliently accommodating relative yielding movement therebetween.

3. A latch bolt comprising a main body portion having a keeper engaging end portion, a sheet metal sheathing disposed around said keeper engaging end portion, resilient material interposed between said sheathing and said keeper engaging end portion, and means for securing said sheathing and said material against displacement from said main body portion.

4. A latch bolt comprising a main body portion having a keeper engaging end portion, a layer of rubber disposed over the extremity and adjacent opposed surfaces of said keeper engaging end portions, and a sheathing disposed over said rubber layer and comprising resilient material having a contracting gripping engagement on said rubber layer and said keeper engaging end portion.

5. A latch bolt comprising a main body portion having a keeper engaging end portion, a layer of rubber disposed over the extremity and adjacent opposed surfaces of said keeper engaging end portion, and a metal sheathing enveloping said layer of rubber having means thereon coacting with said body portion for holding said sheathing and rubber layer against lateral movement with respect to said body portion.

6. A latch bolt comprising a main body portion having a keeper engaging end part provided with recesses in respectively opposite sides thereof, a layer of non-metallic, yieldable sound insulating material enveloping the extremity and said sides of said keeper engaging end part and having reversely bent end portions extending into said recesses, and a generally U-shaped sheet metal sheathing disposed over said layer and having inwardly extending flanges extending into said recesses and disposed between adjacent sections of said said reversely bent end portions of said layer.

7. A latch bolt comprising a main body portion having a keeper engaging end part provided with

5 a pair of spaced recesses in one of two of its opposite sides and a transversely extending groove in the other of said sides, a layer of non-metallic, yieldable sound insulating material enveloping the extremity and said sides of said keeper engaging end part and having reversely bent end portions extending into said recesses, and a sheet

metal sheathing disposed over said layer and having flanges on its opposite extremities, one extending into each recess and said groove respectively and between adjacent sections of the reversely bent portions of said layer.

5

ROY E. BLUE.
